(57) **CLAIM**

I claim the ornamental design for a shoe, as shown and described.

DESCRIPTION

FIG. 1 is a top outer perspective view of a shoe showing my new design;

FIG. 2 is a top inner perspective view thereof;

FIG. 3 is a top view thereof;

FIG. 4 is a front view thereof;

FIG. 5 is a rear view thereof;

FIG. 6 is an inner side view thereof;

FIG. 7 is an outer side view thereof;

FIG. 8 is a bottom view thereof;

FIG. 9 is a top outer perspective view thereof with folded upper;

FIG. 10 is a top inner perspective view thereof with folded upper;

FIG. 11 is a front view thereof with folded upper; and,

FIG. 12 is a rear view thereof with folded upper.

A characteristic feature of the shoe design resides in the shape thereof, including an open outer side portion as shown herein.
